UNITED STATES PATENT OFFICE.

HARRY J. IRVINE, OF BLUE GRASS, IOWA.

RACK-AND-PINION DEVICE.

1,109,420.

Specification of Letters Patent.

Patented Sept. 1, 1914.

Application filed May 7, 1913. Serial No. 766,184.

To all whom it may concern:

Be it known that I, HARRY J. IRVINE, a citizen of the United States, residing at Blue Grass, in the county of Scott and State of Iowa, have invented new and useful Improvements in Rack-and-Pinion Devices, of which the following is a specification.

The invention relates to means for operating the pump rod of a hydraulic jack.

The main object of the present invention is the provision of an operating means and connection for jacks in which the coöperating parts are of simple type and readily interchangeable to vary the length of stroke, the operating means in connection as a whole being designed to work from above, below, or at one side of the jack.

The invention in the preferred form of details will be described in the following specification, reference being had particularly to the accompanying drawings, in which:

Figure 1 is a view in elevation illustrating the improved connection applied to the connecting or pump rod. Fig. 2 is a vertical section on the line 2—2 of Fig. 1. Fig. 3 is a transverse section on the line 3—3 of Fig. 1.

Referring particularly to the accompanying drawing the improved operating means is made primarily of two members one a driving element and the other a driven element. The driving element comprises a pinion 1 fixed upon a shaft 2, operatively mounted in a suitable support 3 and driven in any appropriate or desired manner.

The driven element comprises an elongated member 4 including an annular wall 5 formed to provide a depression 6 throughout its outer contour or edge on the inner side of the bottom or outer wall of this depression is provided a series of teeth 7 of a size and shape to coöperate with the teeth 8 of the pinion. The outer side section of the annular wall 5 is projected beyond the relatively adjacent wall 8 of the depression and is formed with a channel 9 of a size to receive the end 10 of the shaft 2 projecting beyond the pinion, the coöperation of the shaft terminal and channel forming a guide to insure engagement of the pinion with the

adjacent gear teeth 7. The opposing side of the wall 5 is projected laterally at right angles to the adjacent wall 11 of the depression, as at 12 and is then turned outwardly as at 13 forming a guide channel or depression 15, as will be seen in Fig. 3. The bottom wall of the channel 15 thus extends in parallel relation to a closure adjacent the shaft 2 of the pinion, and on said shaft is rotatably mounted a guide 16 having a hook end 17 to seat in the depression. The pinion is thus accurately guided around, and compelled to follow the contour of the wall 5 by the guides described, and hence it will be obvious that in the actuation of the pinion the driven member is given a vertical reciprocating movement. One end of the driven member is formed or provided with a socket or other connector 18 whereby the pump rod 19 may be secured thereto.

It is obvious from the connector and operating means described that a reciprocatory movement will be imparted to the pump rod in the operation of the pinion and that any desired size of driven member may be provided for affording the length of stroke desired.

What is claimed as new, is:

A pump rod operating connection including a support, a driven member, a section of approximately elliptic form, said section being formed with an edge channel provided with teeth on one wall thereof, a pinion coöperating with the teeth, and a shaft mounted in the support and carrying the pinion, said elliptic section being formed with a guiding channel to receive the shaft and hold the pinion in coöperation with the teeth of the member, said member being formed with an additional guiding channel following the contour of the section, and a guiding element carried on the shaft and coöperating with said last mentioned channel, the respective guiding channels being disposed on opposite sides of the pinion.

In testimony whereof I affix my signature in presence of two witnesses.

HARRY J. IRVINE.
